UNITED STATES PATENT OFFICE

151,021

DESIGN FOR A COMBINATION MOPHEAD UNIT

Peter S. Vosbikian and Thomas S. Vosbikian,
Mellrose, Pa.

Application December 6, 1947, Serial No. 143,001

Term of patent 14 years

(Cl. D9—2)

To all whom it may concern:

Be it known that we, Peter S. Vosbikian and Thomas S. Vosbikian, citizens of the United States, residing at Melrose, in the county of Montgomery and State of Pennsylvania, have invented a new, original, and ornamental Design for a Combination Mop Head Unit, of which the following is a specification, reference being had to the accompanying drawing, forming part thereof.

In the drawing, Figure 1 is a perspective view of a combination mop head unit, showing our new design; Figure 2 is an end elevation; and Figure 3 is a front elevation.

The handle socket of Figure 1 is fragmentarily represented in Figures 2 and 3 for convenience of illustration.

We claim:

The ornamental design for a combination mop head unit, as shown and described.

PETER S. VOSBIKIAN.
THOMAS S. VOSBIKIAN.
